KNOB FOR AUTOMOTIVE CIGARETTE LIGHTER OR THE LIKE

Arthur A. Fisher, Scottsdale, Ariz.
(11676 Lakia Drive, Cypress, Calif. 90630)

Filed Mar. 22, 1973, Ser. No. 343,630

Term of patent 14 years

Int. Cl. D8—06; D27—05
U.S. Cl. D8—138

FIG. 1 is a perspective view of a knob for automotive cigarette lighter or the like showing my new design;

FIG. 2 is a top view of the knob on an enlarged scale;
FIG. 3 is a front view thereof, the rear being identical;
FIG. 4 is a side view thereof.

I claim:

The ornamental design for a knob for automotive cigarette lighter or the like, as shown and described.
